Application August 14, 1933, Serial No. 685,042

18 Claims. (Cl. 112—2)

This invention relates to machines, of the general character shown and described in our prior application Serial No. 578,630, filed December 3, 1931, for the continuous quantity production of what is known as tubular upholstery, which is extensively used for the covers of vehicle seat cushions. Such a machine comprises means for supplying and feeding a lining fabric and a finish fabric, means for forming a series of parallel folds in the finish fabric, means for stitching the folds to the lining fabric to form between the fabrics a series of parallel tubes or pipes, and means, operating concurrently with the above instrumentalities, for supplying a cotton batt or other filling material to the tubes or pipes. In the machine forming the subject of the application above referred to, the finish fabric, as well as the lining fabric, is supplied in a continuous length or web. The present invention has for its primary object to provide mechanism whereby the finish fabric can be supplied in separate pieces, each of a size suitable for the formation of an individual cushion cover, without interrupting the continuity of operation of the machine.

The foregoing and other more particular objects of the invention, together with means whereby the latter may be carried into effect, will best be understood from the following description of a preferred embodiment thereof illustrated in the accompanying drawings. It will be understood, however, that the particular construction described and shown has been chosen for purposes of exemplification merely, and that the invention, as defined by the claims hereunto appended, may be otherwise embodied without departure from the spirit and scope thereof.

In said drawings:

Fig. 1 is a side elevation of the substantially complete machine.

Fig. 2 is a fragmentary view of the side opposite to that shown in Fig. 1.

Fig. 3 is a plan view with the sewing mechanism omitted.

Fig. 4 is a longitudinal section, partly broken away.

Fig. 5 is a similar view of a portion of the mechanism shown in Fig. 4, illustrating the elevation of the presser bars to afford access to the feed bars for the purpose of removing or re-arranging the material.

Fig. 6 is an enlarged longitudinal sectional view of a part of the mechanism shown in Fig. 4.

Figs. 7, 8 and 9 are detail sections taken substantially on the lines 7—7, 8—8 and 9—9, respectively, Fig. 6.

Fig. 10 is a fragmentary transverse section taken substantially on the line 10—10, Fig. 4.

Fig. 11 is a fragmentary longitudinal section taken substantially on the line 11—11, Fig. 10.

Fig. 12 is a transverse section, partly broken away, and with certain parts omitted, taken substantially on the line 12—12, Fig. 4.

Fig. 13 is a detail section of one of the pairs of contact members shown in Figs. 15—17 inclusive.

Fig. 14 is a similar view of another pair of contact members.

Figs. 15, 16 and 17 are fragmentary diagrammatic views of the receiving portion of the feeding mechanism and the controlling system therefor, the parts being shown in different positions in the respective views.

The mechanism of the machine is carried by a main frame 25 which, together with certain subsidiary frame elements hereinafter referred to, is suitably designed to provide the necessary supports and bearings for the various operating instrumentalities hereinafter described.

Referring particularly to Figs. 4 and 6, the lining fabric L is supplied in a continuous length or web from a suitable roll or other source, not shown, said fabric being guided in a path converging, toward the stitching point, with the path of travel of the finish fabric F which is fed as hereinafter described, suitable means, generally indicated at 26, being provided for supplying strips of cotton batt or other filling material B (Fig. 4) between said fabrics at or adjacent their point of convergence.

The finish fabric F as it travels toward the stitching point passes over a series of upright forming plates 27 (Figs. 6, 7 and 8) which cooperate with bifurcated presser ribs 29, and which have, in advance of and adjacent the stitching point, upper edge portions 28 which are curved into a substantially horizontal plane, whereby, as the finish fabric is fed toward the stitching point, it is formed with a series of parallel upstanding folds f, the upper edges of which are turned over as indicated at f' in Fig. 7. The turned portions f' of the folds f are thereafter stitched to the lining fabric L by the sewing mechanism which comprises a series of straight, vertically reciprocating needles 30 cooperating with a corresponding series of loopers 31 located in tubular housings 32 which extend between the fabrics.

The parts above referred to, except as hereinafter pointed out and as they enter into combination and cooperate with the parts herein-after described, specifically form no portion of

the present invention and may be substantially as more fully described in our prior application above referred to, or otherwise as preferred.

As above stated, the present invention relates primarily to mechanism whereby the finish fabric is supplied in separate pieces and is suitably gathered for presentation to the fold forming devices and sewing mechanism. Said piece feeding mechanism is supported in part by the main frame 25, including the cross members 34 and 35 thereof, and in part by a frame extension 33 (Figs. 1 and 4), including cross member 36. Said mechanism comprises a feed table 37 supported by the receiving end of the frame extension 33, i. e., the end thereof remote from the main frame, and adapted to receive the cut pieces as hereinafter described; a series of longitudinal feed members, designated as a whole in Figs. 3, 4 and 6 by the numeral 38, for feeding the pieces from the feed table to the fold forming devices and sewing mechanism; and additional feeding devices, generally indicated by the numeral 39 in said figures which cooperate with the looper housings 32 to feed said pieces past said forming devices and sewing mechanism.

The longitudinal feeding devices 38 are arranged in converging relation from the feed table 37 toward the sewing mechanism in order to gather the finish fabric pieces laterally to provide the necessary fullness for the pipes or tubes and for the formation of the folds f. Said feeding devices comprise a series of gyroscopic feed bars 40 (see particularly Figs. 6, 9, 10 and 11) having serrated upper edges, and a corresponding series of presser bars 41 having on their under sides spring fingers 42 for holding the finish fabric pieces F in engagement with the serrated edges of the feed bars 40.

Each of the feed bars 40 operates and is guided between a pair of fixed holding bars 43 also having serrated upper edges for holding the material against retrograde movement. The holding bars 43 are carried by upright portions 44 of angle bars 45 secured, as by screws 46, to the upper ends of bifurcated brackets 47 which in turn are bolted or otherwise secured to and supported by the cross members 34, 35, and 36. Each feed bar 40 has secured thereto (Figs. 6 and 9) a number of slotted lugs 49; said bars being received in the slots in the lugs and being secured therein by rivets 48, and the upright portions 44 of the angle bars 45 being cut away, as shown at 50, to receive said lugs. The lugs 49 are formed with T-shaped heads 51 which are received in undercut grooves 52 in enlargements 53 at the upper edge of an actuating bar 54. Each of the actuating bars 54 is formed at its lower edge with flanged portions 55 (Figs. 6 and 11) to which are secured, as by bolts 56, brackets constituting eccentric straps 57.

In the construction shown, each actuating bar 54 is provided with three eccentric straps 57, corresponding straps of the several bars cooperating with eccentricities 58 (Figs. 4, 10 and 11) on transverse shafts 59, 60 and 61 journaled in the brackets 47 carried respectively by the several cross members 34, 35 and 36. Each of the shafts 59, 60 and 61 has keyed thereto, at a point approximately midway of its length, a skew gear 62 which meshes with a skew gear 63 keyed to a longitudinal shaft 64. The shaft 64 is journaled in suitable bearings 65 carried by one of the brackets 47 of each set at approximately the longitudinal center of the machine, said last named brackets and those immediately adjacent

thereto being suitably formed to receive said bearings and the gears 63, as shown most clearly in Fig. 10. The shaft 64 has fast thereon a skew gear 66 (Fig. 4) which meshes with a skew gear 67 on a transverse shaft 68 journaled in bearings in a bracket 341 carried by the cross member 34 and in another bracket 69 (Fig. 3) carried by the frame extension 33. The shaft 68 is connected through suitable power transmitting elements, including beveled gears 70, chain and sprocket gearing 71, and belt 72 (see also Fig. 2), with an electric or other motor 73 carried by the main frame 25. The eccentricities 58 serve to impart a gyroscopic motion to the feed bars 40, whereby the material is intermittently advanced toward the sewing mechanism, said material being held against retrograde movement, during the intervals between the feeding movements, by the holding bars 43.

The feeding devices 39 comprise relatively short parallel feed bars 24 (see particularly Figs. 6, 7 and 8) each having preferably a plurality of serrated edges located opposite the corresponding looper housing 32, said feed bars being carried by actuators 23 and being urged upwardly with respect to said actuators toward the looper housings by springs 22. The several actuators 23 are pivotally connected at 21 to the corresponding actuating bars 54 and are formed with portions 20 which constitute eccentric straps embracing eccentricities 19 on a transverse shaft 18 suitably journaled in the frame extension 33. The shaft 18 is provided with a skew gear 17 which meshes with a skew gear 16 (Fig. 4) on the shaft 64. By means of this mechanism the serrated feed bars 24 are given a gyroscopic motion similar to that imparted to the feed bars 40 and cooperate with the looper housings 32 to continue the feed of the finish fabric pieces F to the sewing mechanism beyond the ends of the feed bars 40.

Each of the presser bars 41 comprises a fixed section 74 (Fig. 4) suitably secured to the frame, a hinged section 75 pivoted at 76 to the section 74, and a clamping section 77 (see also Figs. 15, 16 and 17) pivoted at 78 to the free end of the section 75. The sections 75 of the several presser bars are supported by hangers 79 (see Fig. 12) from a tubular cross head 80 connected at its ends by a pair of links 81 with arms 82 on a cross shaft 83 journaled at its ends in uprights 84 rising from the frame extension 33. The shaft 83 is provided at its ends with cranks 85 whereby said shaft may be turned to lift the hinged sections 75, with their pivoted sections 77, from the normal position shown in Fig. 4 into the elevated position shown in Fig. 5 to permit removal or rearrangement of the cloth in case of necessity. The links 81 are preferably of the angular form shown, whereby the pivots connecting said links with the arms 82 move beyond the dead center position when the parts are moved into the position shown in Fig. 5, thereby serving to retain said parts in said position. It will be understood that this is an emergency expedient for use only in case of accidental improper operation, and that the hinged sections 75 normally occupy the position shown in Fig. 4.

Journaled in suitable bearings in the tubular cross head 80, and extending therethrough and beyond the ends thereof, is a shaft 86 having on each end a pair of oppositely extending arms 87 and 88. The arms 87 are connected by links 89 with the cores 90 of a pair of solenoids 91 carried by the frame extension 33. The arms 88 are connected by links 92 with the plungers 93 of a pair

of dash pots or oil checks 94 likewise carried by the frame extension 33. The pins 95 and 96, for connecting the links 89 and 92 with the cores 90 and plungers 93 respectively, are removable to permit the elevation of the hinged sections 75 of the presser bars into the position shown in Fig. 5, as above explained. The arms 88 are pivotally connected at their ends with arms 97 on a transverse shaft 98 journaled in hangers 99 by which the several swinging clamping sections 77 of the presser bars are supported, said shaft serving to connect all of said sections for movement on their pivots as a unit. At its ends the shaft 98 is provided with arms 100 provided with pins 101 adapted to cooperate with hooks 102 pivoted to the cores 103 of solenoids 104 carried by the frame extension 33. The hooks 102 have cam portions 105 which cooperate with pins 106 on uprights 107 rising from the frame extension 33, whereby when the solenoids 104 are energized the hooks 102 are moved from the position shown in Fig. 16 to that shown in Fig. 17 and are caused to engage the pins 106 and draw the arms 100 and clamping sections 77 downward. The pins 108 by which the hooks 102 are pivotally connected with the cores 103 are connected by springs 109 with the frame extension 33, whereby the hooks 102 are returned to the position shown in Figs. 15 and 16 when the solenoids 104 are de-energized.

Journalled in suitable bearings in the frame extension 33 is a cross shaft 110 having at each end a three-armed lever 111, each lever comprising an upwardly extending arm 112, a downwardly extending arm 113, and a laterally extending arm 114. The arms 112 of the levers 111 are connected by a cross bar 115 adapted, when said levers are moved from the position shown in Figs. 15 and 17 into the position shown in Fig. 16, to cooperate with the feed table 37 to clamp the edge of a piece of fabric thereon. The arm 114 of each lever is connected with the frame extension 33 by a spring 116 adapted, when said lever is moved between the two positions referred to, to pass dead center, thereby tending to hold said lever in either of the two positions into which it is moved. The arm 114 of each of the levers 111 is connected by a link 117 with a suitable treadle 170 (see Figs. 1 and 3). The arms 113 of the levers 111 are connected by links 118 with bell crank levers 119 pivoted at 120 to brackets 121 carried by the uprights 84, said bell crank levers having arms 122 which extend into the path of movement of the shaft 98 when the clamping sections 77 of the presser bars are depressed into their normal operative position.

Carried respectively by one of the angle bars 45 and the hinged section 75 of the corresponding presser bar 41, at a suitable point a short distance from the receiving end of said section, are cooperating contact members 123 and 124. As shown most clearly in Fig. 13, the contact member 124 is fixed to the presser bar, while the member 123 is slidably mounted in a socket 125 secured to the bar 45 and is normally urged toward the contact member 124 by a spring 126, whereby said contact members will engage one another when there is no cloth therebetween, as shown in Fig. 15, but will be forced apart and held separated when the cloth is fed therebetween, as shown in Figs. 13, 16 and 17.

Similar cooperating contact members 127 and 128 are carried respectively by one of the angle bars 45 and the pivoted clamping section 77 of the corresponding presser bar. The latter con-

tact members differ from those last described in that both are movable and normally urged toward one another by springs 129 and 130 (Fig. 14) so as to have a somewhat greater range of movement.

Similar contact members 131 and 132 are also carried respectively by the pivoted clamping section 77 of one of the presser bars and a bracket 133 carried by the corresponding hanger 79.

Carried by the casing of one of the solenoids 104 and a bracket 134 secured thereto are two normally separated contact members 135 and 136, the contact member 135 being adapted to be moved into engagement with the contact member 136 by the core 103 when said solenoid is 15 energized.

One of the three-armed levers 111 is provided with a switch element 137 adapted to engage a cooperating switch element 138, fixed to the frame extension 33, when said lever is in the 20 position shown in Figs. 15 and 17 to close the circuit therethrough, but to disengage the same and break the circuit when said lever is in the position shown in Fig. 16.

The cores 90 of the solenoids 91 are formed 25 with shoulders 139 adapted to be engaged by latch members 140 carried by the cores 141 of solenoids 142 and normally urged toward operative position by springs 143, whereby, when the solenoids 91 and 142 are all de-energized, the 30 downward movement of the pivoted clamping sections 77 of the presser bars from the elevated position shown in Fig. 15 toward the operative position shown in Fig. 17 is arrested as shown in Fig. 16.

The circuits connecting the several electrical devices above referred to are illustrated in Figs. 15, 16 and 17. For simplicity the circuits to one each of the solenoids 91, 104 and 142 are shown, but it will be understood that other circuits, suitably connected in parallel with the circuits shown and described beyond their several controlling contact devices and switches, extend to the corresponding solenoids at the opposite side of the machine.

Conductors 144 and 145, connected with the opposite poles of a suitable source of current, are connected respectively with the switch element 138 and the contact member 124. Cooperating contact member 123 is connected by 50 a conductor 146 with one end of the winding of the solenoid 91 the other end of which is connected by a conductor 147 with the switch element 137, thereby completing the circuit through the solenoid 91 when the contact members 123 and 124 are in engagement and the switch 137, 138 is closed. A parallel circuit through the winding of the solenoid 91 through the contact members 131 and 132, and independent of the contact members 123 and 124, is provided by a 60 conductor 148 connecting the conductor 145 with the contact member 132 and a conductor 149 connecting the contact member 131 with the conductor 146 adjacent the solenoid 91, or between the latter and the contact member 123. 65 A conductor 150 leads from the contact member 132, through the normally closed switch element 151 of a retarded relay 152, to the contact member 128. The cooperating contact member 127 is connected by a conductor 153 with one end 70 of the winding of the solenoid 104 the other end of which is connected by a conductor 154 with the conductor 144. A shunt circuit 155 to the coil of the retarded relay 152 is connected about the solenoid 104 to the conductors 153 and 154 75

respectively. Leading from the conductor 153 to one end of the winding of the solenoid 142 is a conductor 156, the opposite end of said winding being connected with the conductor 154 by a conductor 157, thereby providing a parallel circuit through the solenoid 142 between the conductors 153 and 154 about the solenoid 104. A conductor 158 leads from the conductor 150 to the contact member 135, the cooperating contact member 136 being connected by a conductor 159 with the conductor 156, whereby the contact members 135 and 136 are adapted to close the circuits to the solenoids 104 and 142 independently of the contact members 127 and 128.

In Figs. 15, 16 and 17 the parts are shown in various positions assumed thereby during different stages in the operation of the machine. For clearness of illustration, in each figure the circuits which are closed in the position shown are shown in full lines, while the open circuits are shown in dot-and-dash lines.

In Fig. 15 a piece of finish fabric F¹ is shown as having been fed toward the forming and sewing mechanisms to a point where its rear (in the direction of travel) edge has passed the contact members 123 and 124, the forward edge of the next succeeding piece F² having not yet reached said contact members, thereby providing a gap between the pieces and permitting said contact members to engage one another. A circuit is, therefore closed through the conductor 145, contact members 123 and 124, conductor 146, solenoid 91, conductor 147, switch 137, 138, and conductor 144. The solenoid 91 is therefore energized drawing its core 90 downwardly and raising the pivoted clamping sections 77 of the presser bars 41 into the position shown. The raising of the sections 77 engages the contact members 131 and 132 thereby closing a circuit through the solenoid 91 independently of the contact members 123 and 124, through the conductors 148 and 149. Consequently, when the forward edge of the piece F² reaches and separates the contact members 123 and 124, the solenoid 91 will remain energized and continue to hold the clamping sections 77 in the raised position shown.

The operator then takes a piece of material F³ (Fig. 16) from a stack S (Figs. 1 and 3) on a conveniently located truck or platform T, and places it on the feed table 37 with one edge beneath the clamping bar 115 and the other edge beneath the raised pivoted clamping sections 77 and overlying the adjacent edge of the piece F². He then operates either of the treadles 110 which through its link 117, moves the three-armed levers 111 into the position shown in Fig. 16, thereby clamping the piece F³ to the feed table 37 against feeding movement. The continued feeding movement of the piece F² in engagement with the piece F³ causes the latter to be drawn or smoothed out into flat position, straightening out any wrinkles therein. Movement of the three-armed lever 111 into the position shown in Fig. 16 opens the switch 137, 138, thereby breaking the circuit through the solenoid 91. The clamping sections 77 are, therefore, released and permitted to fall toward normal position, this movement being cushioned by the dash pots 94. Before reaching normal position, however, the downward movement of the sections 77 is arrested by engagement of the shoulder 139 on the core 90 with the latch member 140, so that said sections of the presser bar remain inoperative to cooperate with the feed bars 40 to feed the piece F³.

When the parts are in the position last described, and as shown in Fig. 16, the piece F² still occupies a position between the contact members 127 and 128, but, as the feeding of said piece continues, it moves out of this position and permits engagement of said contact members as shown in Fig. 17. A circuit is thereupon closed through conductors 145 and 148, contact member 132, conductor 150, including the normally closed switch element 151 of the retarded relay 152, contact members 128 and 127, conductor 153, solenoid 104, and conductors 154 and 144, this circuit being independent of the switch 137, 138 which as above explained, has been previously opened. This also closes the parallel circuit about the solenoid 104 through the conductors 156, 157 and the solenoid 142. The energization of the solenoid 142 causes the core 141 and the latch 140 thereof to be withdrawn from engagement with the shoulder 139 on the core 90 of the solenoid 91, thus releasing the latter core and the pivoted clamping sections 77, while the energization of the solenoid 104 causes the core 103 and hook 102 to be drawn downwardly into the position shown in Fig. 17, thereby moving the pivoted clamping sections 77 into their normal position and rendering the feeding mechanism operative to feed the piece F³. At the same time the shaft 98, by engagement with the arm 122 of the bell crank 119, causes said bell crank to operate, through the rod 118, to return the three-armed lever 111 to its normal position shown in Figs. 15 and 17, thereby releasing the piece F³ and permitting feeding thereof. The energization of the solenoid 104, and consequent downward movement of its core 103, engages the contact members 135 and 136, thereby closing the circuit through said solenoid and the solenoid 142, independently of the contacts 127 and 128, through the conductors 158, 156, 159. Consequently, when the piece F³ is fed between the contact members 127 and 128, separating said contact members and breaking the circuit at that point, said circuit remains closed through contact members 135 and 136 to maintain the clamping sections 77 in the position shown in Fig. 17, and continuing the feeding of said piece. When the circuit through the solenoid 104 is closed, the shunt circuit through the core of the retarded relay 152 is likewise closed, so that after a predetermined period, sufficient to permit the forward edge of the piece F³ to pass beyond the pivoted sections 77 and under the hinged sections 75, the circuit through the conductor 150 is broken, de-energizing the solenoid 104, and permitting the spring 109 to restore the hook 102 to its normal position as shown in Figs. 15 and 16. Breaking the circuit through the solenoid 104 likewise breaks the circuit through the solenoid 142 as well as the shunt circuit 155 through the retarded relay, leaving the latch member 140 to the influence of its spring 143, and permitting the switch element 151 of the retarded relay to again close the circuit through the conductor 150, thereby restoring the system to its original position, completing the cycle, and permitting a reclosing of the circuit through the contact members 123 and 124 and solenoid 91 when the rear edge of the piece F² passes beyond said contact members in the same way as above described in connection with the piece F¹.

It will be understood that, while for convenience and brevity the term "fabric" is used herein to designate the material F, this expression is not to be taken as limited to textile materials, but

is intended to include any and all sheet materials suitable for the purpose in question.

We claim:

1. A machine of the character described having mechanism for assembling two sheets of fabric in superimposed relationship and forming a series of parallel folds in one of said sheets, and means for stitching the other of said sheets to said parallel fold, characterized by the fact that 10 said mechanism includes means for feeding and gathering said one sheet comprising a series of gyratory feed bars disposed in converging relation.
2. A machine of the character described having mechanism for assembling two sheets of fabric in superimposed relationship and forming a series of parallel folds in one of said sheets, means for stitching the other of said sheets to said parallel folds, and other means for feeding 15 the assembled sheets past said stitching means characterized by the fact that said mechanism includes means for feeding and gathering said one sheet comprising a series of gyratory feed bars disposed in converging relation.
3. A machine of the character described having mechanism for assembling two sheets of fabric in superimposed relationship and forming a series of parallel folds in one of said sheets, and means for stitching the other of said sheets to 20 said parallel folds, characterized by the fact that said mechanism includes means for feeding and gathering said one sheet comprising a series of gyratory feed bars disposed in converging relation, and a series of parallel gyratory feed bars 25 for feeding the assembled sheets past said stitching means.
4. In a machine of the character described, fabric piece feeding mechanism including co-operating elements adapted to engage the fabric at opposite sides, and means controlled by the fed position of a previously inserted piece for 30 separating said elements at the receiving end to permit the introduction of a following piece.
5. In a machine of the character described, fabric piece feeding mechanism including co-operating elements adapted to engage the fabric at opposite sides, and means controlled by the fed positions of previously inserted pieces for 35 separating said elements at the receiving end to permit the introduction of a following piece and for thereafter closing said elements upon said following piece to start the feeding thereof.
6. In a machine of the character described, fabric piece feeding mechanism including a series 40 of feeding elements and a corresponding series of presser bars for pressing the fabric into engagement with said feeding elements, said presser bars having pivoted sections at the receiving end of the mechanism, and means controlled by the fed positions of previously inserted pieces for moving said sections on their pivots 45 away from the feeding elements to permit the introduction of a following piece and for thereafter restoring said sections to normal position 50 to start the feeding of said following piece.
7. In a machine of the character described, fabric piece feeding mechanism, a feed table, means for clamping a piece to said table with an edge thereof in position to be engaged by said feeding mechanism, and means controlled by the fed position of a previously inserted piece for 55 releasing said clamping means and engaging said first named piece with said feeding mechanism to start the feeding thereof.
8. In a machine of the character described, 60 fabric piece feeding mechanism including co-operating elements adapted to engage the fabric at opposite sides, means at the receiving end of said mechanism for holding a piece against feeding, and means controlled by the fed position of a previously inserted piece for separating said elements at said receiving end to permit the introduction of said held piece, for releasing said holding means, and for closing said elements upon said last named piece to start the feeding thereof.
9. In a machine of the character described, fabric piece feeding mechanism including a feeding element and a presser element for holding the material in engagement with said feeding 15 element, said presser element having at its receiving end a section movable into an inoperative position away from said feeding element, and means jointly controlled by a piece being fed and by said movable section for moving said 20 section into inoperative position and retaining the same therein.
10. In a machine of the character described, fabric piece feeding mechanism including a feeding element and a presser element for holding 25 the material in engagement with said feeding element, said presser element having at its receiving end a section movable into an inoperative position away from said feeding element, means including a solenoid for moving said section 30 into inoperative position, and means jointly controlled by a piece being fed and by said movable section for controlling the circuit to said solenoid.
11. In a machine of the character described, fabric piece feeding mechanism including a feeding element and a presser element for holding the material in engagement with said feeding element, said presser element having at its receiving end a section movable into inoperative 35 position away from said feeding element, means controlled by a piece being fed for moving said section into inoperative position, a clamp for holding a second piece in position to be fed, and means controlled by a piece intermediate said 40 first named pieces for releasing said clamp and restoring said movable section to operative position.
12. In a machine of the character described, fabric piece feeding mechanism having at the 45 receiving end portions relatively movable into work receiving and work feeding positions, means controlled by the position of a piece being fed for moving said portions into work receiving position, clamping means for a piece to be fed, 50 means controlled by said clamping means for controlling said moving means, means for arresting the return of said portions into work feeding position, and means controlled by the fed position of an intermediate piece for releasing 55 said clamping means and arresting means.
13. In a machine of the character described, fabric piece feeding mechanism including a feeding element and a presser element for holding material in engagement with said feeding 60 element, said presser element having at its receiving end a section movable into an inoperative position away from said feeding element, means including a solenoid for moving said section into inoperative position, means controlled 65 by a piece being fed for controlling the circuit to said solenoid, a clamp for holding a piece to be fed with an edge thereof in a position to be engaged by said feeding mechanism, a switch 70 operated by said clamp for breaking the circuit 75

to said solenoid when said clamp is in operative position, a latch for arresting the return of said movable section to normal position, a solenoid for releasing said latch, and means controlled by the fed position of an intermediate piece for energizing said last-named solenoid and for releasing said clamp.

14. In a machine of the character described, fabric piece feeding mechanism having at the receiving end portions relatively movable into work receiving and work feeding positions, means controlled by the position of a piece being fed for moving said portions into work receiving position, clamping means for a piece to be fed, and means controlled by the fed position of an intermediate piece for moving the portions of said feeding mechanism into work feeding position and for releasing said clamping means.

15. In a machine of the character described, fabric piece feeding mechanism including a feeding element and a presser element for holding the material in engagement with said feeding element, said elements having at the receiving end relatively separable portions, means including a solenoid for separating said portions, means controlled by a piece being fed for controlling the circuit to said solenoid, a clamp for holding a second piece against feeding, means including a second solenoid for closing the parts of said feeding mechanism upon said second piece and for releasing said clamp, and means controlled by the fed position of an intermediate piece for controlling the circuit to said second solenoid.

16. In a machine of the character described, fabric piece feeding mechanism having at the receiving end portions relatively movable into work receiving and work feeding positions, means for moving said portions into work receiving position, means for moving said portions into work

feeding position, clamping means for a piece to be fed, means controlled jointly by said clamping means and by the position of a piece being fed for controlling said first named moving means, and means controlled by the position of another piece being fed for controlling said second named moving means and said clamping means.

17. In a machine of the character described, fabric piece-feeding mechanism having at the receiving end portions relatively movable into work-receiving and work-feeding positions, means controlled by the position of a piece being fed for moving said portions into work-receiving position, clamping means for a piece to be fed, means controlled by said clamping means for controlling said moving means, means for arresting the return of said portions into work-feeding position, and means controlled by the fed position of an intermediate piece for releasing said clamping and arresting means and for moving said portions into work-feeding position.

18. In a machine of the character described, fabric piece-feeding mechanism having at the receiving end portions relatively movable into work-receiving and work-feeding positions, means including a solenoid for moving said portions into work-receiving position, means controlled by a piece being fed for controlling the circuit to said solenoid, a clamp for holding a second piece against feeding, means including a second solenoid for moving said portions into work-feeding position and for releasing said clamp, means jointly controlled by the fed position of an intermediate piece and by said second solenoid for controlling the circuit to the latter, and a retarded relay connected in parallel with said second solenoid for controlling the circuit thereto.
